UNITED STATES PATENT OFFICE.

EDWARD A. EVERETT, OF LONG ISLAND CITY, NEW YORK, ASSIGNOR TO NANDE CORPORATION, A CORPORATION OF NEW YORK.

TRACK-DRILLING MACHINE.

Application filed June 15, 1925. Serial No. 37,397.

This invention relates to track working machines, that is to machines for working on a rail of a railway track such as drilling the rail and has for an object to improve upon machines of this class by enabling them to clamp against the rail at a joint having splice bars, by adjusting the clamping arrangement to the rail so that the point of the drill may be seen when the machine is in operation, by providing a gage for locating the drill point from marks on top of the rail and by the construction and arrangement of parts as more fully described in the following specification and shown in the accompanying drawings, in which, Fig. 1 is a side elevation of a drilling machine complete embodying the features of my invention, Fig. 2 is a plan view of the machine shown in Fig. 1, Fig. 3 is an enlarged detail showing in transverse elevation the mechanism for clamping the machine to the rail, Fig. 4 is a side elevation and Fig. 5 is an end elevation of the clamping member which engages the web of the rail, Fig. 6 shows in elevation the relation of the clamping member to the splice bar of the rail, Fig. 6^a is a detail, partly in section, showing the method of latching the clamping member in place and Fig. 7 is a rail end showing the method of locating the drilling from marks on top of the rail.

This invention is a continuation of and an improvement upon the invention disclosed in my co-pending application, Serial No. 731,327, filed August 11, 1924. In the application referred to, the machine is arranged to drill the web of the rail with the splice bars removed. In practice it is often necessary to drill the rail with the splice bars in place and for this purpose, in the present application, I have arranged the clamping member opposite the drill to engage the rail by a plurality of stages; one stage is effective when the clamping member rests against the splice bar and another stage is effective when the clamping member rests against the web of the rail. The locking member on the same side of the rail with the drill is adjustably positioned on its operating shaft with the object of locating it, under normal conditions, so that the point of the drill can be seen as it enters the rail and at the same time enabling it to be located close to the vertical line of the drill when drilling a stub ended rail close

to the rail end. According to general practice the rail is marked for drilling purposes by a chalk mark across the top of the rail and in the present construction I have provided a gaging system whereby the drill point may be correctly located from these chalk marks on the rail head without locating the centre of the drill hole on the web of the rail. In the present invention the operating levers are all arranged on the drill side of the rail and are readily accessible from the point where the drill is manipulated.

Referring to the drawings, 11 is the track rail which at the joints is provided with splice bars 12—12 as shown in Fig. 1. The machine rolls along the rail on rollers 13—13 which support the frame members 14 and 15. The machine is substantially balanced on these rollers having the gasoline motor 17 on one side of the rail and the drilling mechanism on the opposite side. The frame member 15 through the pedestal 16 supports the motor 17 having a magneto 18 and fly wheel 19 mounted on shaft 20 and through a train of gears in the housing 21, 22, 23 and 24 drives the drill spindle 25 opposite the web of the rail. This spindle is positioned by the adjustable foot 26 resting on the ties and is fed by the hand wheel 27 and 80 the controlling lever 28. A rest 29 is provided for supporting the machine in combination with 26 when it is off the track. For this purpose the rest 29 may be placed in the vertical position as shown in Fig. 3 and 90 when not in use, may be turned to the horizontal position as in Fig. 1 so as to clear the rail when the machine is removed from the track. Handles 30—30 are provided for lifting the machine off the track and a pipe 95 rail 32 is provided whereby the machine may be conveniently rolled along the track. Vertical screws 31—31 are arranged to support the machine on the top of the rail close to the line of the drill spindle and independently of the rollers 13.

The machine is locked to the rail when the drill is in operation by the handle 33 which is latched by the detent 34 to quadrant 35. This handle is secured on shaft 36 placed 105 parallel with the rail and arranged to rotate in bearings 42—42. The locking mechanism 37 is clamped to this shaft and carries the ball ended screw 38 which is locked in position in 37 by the hand wheel 39. The ball 110

38 may be arranged to engage the shoulder of the splice bar 12 as indicated in Fig. 1, or it may be arranged to engage under the head of the rail and holds the machine in place and prevents it from rising on the rail. Two mechanisms 37 and 37' are provided on this shaft spaced on either side of the line of the drill spindle whereby the machine is rigidly held where the drill engages the rail. The mechanism 37 is splined on shaft 36, the stud 40 engaging the spline so that this mechanism can slide on the shaft and can be located away from the drill spindle so that the latter may be inspected while it is in operation. However, when the machine reaches the stud end of a rail with no abutting rail to rest upon, it is then necessary to move this mechanism as close as possible to the centre of the machine so that it is in position to engage the rail.

The machine is held in position against the thrust from the drill by a clamping device which engages the web of the rail opposite the drill. This device is shown in Figs. 4, 5 and 6 and comprises the quadrant 51 pivoted on a shaft 52 and having a forked end at 53 directly opposite the drill with enlarged wings 54. This quadrant is latched in the engaging position against the rail by pin 57 entering aperture 55 and it is latched in the engaging position against the splice bar by the pin 57 engaging the end of slot 56 as indicated in Fig. 6. The pin 57 is controlled by lever 59 on the end of shaft 60 which rotates in bearings 61 and 62 and is operated by handle 63. A spring 58, Fig. 2 engages an arm depending from 60 which tends to hold pin 57 in engagement with 51.

When the machine is brought to a drilling location, the handle 72 is raised which, though lever 71 is connected with shaft 52 and thereby the quadrant is lowered until it engages the web of the rail when pin 57 is automatically forced into the aperture 55 and the quadrant is thereby latched in position until handle 63 is raised withdrawing pin 57 and permitting quadrant 51 to be raised by the action of coil spring 73 on shaft 52 or by the counterweight of handle 72 itself. When the machine is located opposite a splice bar, the handle 72 is raised as before until it is stopped by the quadrant engaging the splice bar. In this position pin 57 enters slot 56 and latches the quadrant in position until released by handle 63 as has been described. It will be noted that due to the action of spring 58, pin 57 is normally biased to latch the quadrant and if an aperture were provided at 56 similar to the aperture at 55 the pin would latch the quadrant so that it could not be moved to its extreme position. The latching position 56 is therefore formed in a slot providing a free movement of the quadrant towards its extreme position. This is a matter of consid-

erable importance in handling the machine as usually the operator has only one hand available for operating handles 63 and 72. The use of the shaft 60 brings these handles close together and locates them conveniently at the point where the operator stands in manipulating the machine.

Gages are provided for positioning the machine by the rod 81 secured in lug 82 on the frame and carrying the index fingers 83 and 84 projecting over and close to the rail head. These fingers may be spaced by the graduated scale as indicated at 85. If the machine is rolled along the rail as in Fig. 7 until finger 84 registers with line *a* then the drill will be in position to drill the rail at *a'*. If now the machine is moved until finger 83 registers with line *a* then the drill will be in position to drill the rail at *b'*; the fingers 83 and 84 being spaced according to the spacing of *a'* and *b'*. Where only one index finger is used as shown at the opposite end of the machine on rod 81' then the top of the rail is chalk marked at *a* and *b* as indicated in Fig. 7 and the finger 83' is registered successively with each of these marks. The chalk marks on the rail are, of course, located with reference to the position of the drilling from the end of the rail.

Having thus described my invention, I claim:

1. In a track drilling machine of the type having a frame positioned above the track rail and extending a substantial distance upon both sides thereof and means for supporting the frame on the top of the track rail and an adjustable abutment secured to the frame and having two positions, one to bear on the track rail and the other to bear on a splice-bar on one side of the track rail, the combination of a member bearable on the track rail or a splice-bar on the other side of the track rail, a pivot pin supported by said frame upon which said member is mounted, a spring controlled latch for preventing movement of said member from its said two bearing positions, a manually operable member for withdrawing said latch, a lever for moving said member into either of its bearing positions wherein it is restrained by said latch and a spring for moving said member out of its bearing positions upon a manual operation of said latch.

2. In a track drilling machine clamping means, in combination; a clamping member having a first clamping position, a second clamping position; and a free position; a pivot upon which the member is mounted for pivotal movement; a latch positioned to coact with the clamping member and restrain it from movement out of either of its two clamping positions; manual means for operating the latch to release; spring means for moving the member from the first clamping position to the second when the

- latch is operated to release and manual means for moving the clamping member to the first of its clamping positions and to its free position.
5. In a track drilling machine, in combination, a frame; a clamping member having a first clamping position, a second clamping position, and a free position; said clamping member being formed with two spaced abutments; a pivot pin supported by the frame upon which the clamping member is mounted; a latch supported by the frame and movable to three positions, one in which it contacts with one of the abutments to 10 hold the clamping member in said first clamping position, another in which it contacts with the other abutment to hold the clamping member in said second clamping position, and a third in which it is out of the 15 path of both abutments to allow said member to move to its free position; means for moving said latch to its said several positions, and means for automatically moving said clamping member when it is released by 20 the latch to either of the positions specified.
25. In a track drilling machine, in combination; a clamping member; means for sup-
- porting the clamping member for pivotal movement; said clamping member formed with two cavities, one of said cavities being 30 more extensive than the other, but partially coinciding with and overlapping the other; a reciprocatable latch for contact with the walls of said cavities whereby when said latch is in the smaller cavity pivotal 35 movement in both of two directions of the clamping member is prevented and when the latch is in the more extensive cavity pivotal movement in one only of the two directions is permitted.
- 40
5. The combination, in a machine for working on rails of a railway track, of a frame supported on the rail by rollers, a mechanism embodied in said frame having a tool for operating on the web of the rail, an 45 index rod secured to said frame having a plurality of index fingers extending towards the rail whereby said tool may be located in a plurality of predetermined positions with reference to marks on the rail.
